UNITED STATES PATENT OFFICE.

RODERICK WASHINGTON DAVIES, OF CANTON, OHIO, ASSIGNOR TO AMERICAN CASTING MACHINE COMPANY, A CORPORATION OF NEW JERSEY.

APPARATUS FOR CASTING METAL.

SPECIFICATION forming part of Letters Patent No. 726,878, dated May 5, 1903.

Application filed February 25, 1901. Serial No. 48,680. (No model.)

To all whom it may concern:

Be it known that I, RODERICK WASHINGTON DAVIES, engineer, of Canton, State of Ohio, have invented certain new and useful Improvements in Apparatus for Casting Metal and other Substances Suitable for Casting, Especially Casting Iron Into Pigs, of which the following is a specification, illustrated by the accompanying drawings, which form part of this specification.

This present invention is an improvement upon certain types of automatic casting apparatus, one form of which is exemplified in my United States Patent, granted February 21, 1899, No. 620,020. In that patent there is shown and described a series of molds which are mounted upon a continuously-traveling support or carrier, so as to bring them successively into position to be filled with the molten metal, thereafter dumped or turned off to discharge the metal after it has solidified, and thereafter preferably the molds are doped or coated with lime or other protective material before being filled with molten metal to prevent the metal from sticking to the mold. The molds in this class of apparatus have generally been mounted pivotally upon the traveling carrier, so that they can be overturned at the place where it is desired to discharge the pigs from the mold. Special devices and expedients—such, for example, as springs—have been utilized for restoring and maintaining the molds in their normal and proper position for filling. One object of the present invention is to improve the apparatus in this respect by utilizing hoods or roof-like shields that prevent the molten metal from pouring out through the spaces between neighboring molds in such a way as to cause these hoods to maintain and secure the molds in their proper position during the casting operation.

Difficulty has also arisen in suitably cooling the metal before it is dumped into the cars without resorting to the necessity of plunging the metal into cold water, as this is very objectionable to certain grades of metal. One object of the present invention is to obviate the necessity of plunging the metal into water by the use of cooling-bins or storage-receptacles in combination with a traveling

carrier for the molds of such size that the metal will be solidified and partially cooled before it is dumped into the bins and will be further cooled in the bins by the air draft which the hot metal produces in the bin.

In the accompanying drawings one embodiment of the invention is shown, omitting, however, such parts in detail as will be obvious to those skilled in the art.

Figure 1 is a general plan view of the parts of the complete apparatus that are directly connected with the present improvements. Fig. 2 is a partial vertical cross-section on the plane 2 2 of Fig. 1. Fig. 3 is an elevation of parts of the traveling carrier of the molds and hoods slightly distorted, so as also to appear as viewed radially or endwise of the molds, and also showing the fixed incline by which the hoods are raised at certain times. Fig. 4 is a detail view of one of the molds with its star-wheel for overturning it. Fig. 5 is a detail view of one of the hoods. Fig. 6 is a cross-section of one of the molds.

The present invention is not concerned in the particular form of the carrier employed, though the horizontally-rotating-wheel form, which has been successfully employed in several instances, has been chosen for illustration. Such a carrier may consist of a central support *c*, centered by an axial pin *d* and turning on ball-bearings; radial girders *e*, provided with a rail *f*, secured beneath the girders and traveling upon the fixed rollers or wheels *f'*; a rack *g*, which extends all the way around the wheel beneath the girders and is actuated by the pinion *g'* from a suitable driving-engine *g''* or other source of power and which should cause the wheel to make a complete revolution in one or two minutes, and molds *h* and mold-actuating devices mounted upon the carrier-wheel.

The molten metal should be delivered to the molds in a continuous stream from a chute or other suitable supplying device, as at *j*, and roof-shaped hoods *l* should be provided to bridge over the intervals between adjacent molds, so that the stream of metal in falling upon one of these hoods as the molds and hoods travel beneath it will be delivered properly into the neighboring molds. The molds and their attachments and operation will now

be described. The shape of the mold, as shown, is not novel. It is the same as that shown in the previous patent mentioned above. Preferably each mold will have four 5 mold-recesses, so that four pigs can be successively cast in the mold before twice using the same mold-recess. Each mold h has a trunnion or axle h' at each end, one of which axles, preferably the outer one, is provided with a star-wheel m , having arms corresponding to the several mold-recesses. In the example illustrated there are four arms to the star-wheel m , because there are four recesses in each mold. When the metal is being cast, only one of the mold-recesses is filled with metal. In order to insure it being placed with its rim horizontal, the hoods l are made to rest upon the edges of the two adjacent molds, as seen at the extreme left hand of Fig. 15

20 3. After the uppermost recess of the mold has been filled with the metal and after the metal has cooled sufficiently the mold is dumped or discharged by first raising the hoods l at each side of it and then causing a fixed tripping post or arm to strike the star-wheel m , upsetting the mold and dropping the pig-iron out of it. These fixed tripping-arms (of which there may be preferably three) or obstructions are marked, respectively, p p' p'' 25 in Figs. 1, 2, and 3. The means of supporting them and the position in which they should be placed will be described farther along. The star-wheels m should be so proportioned that they will strike the successive 30 tripping posts or arms p and be turned about ninety degrees by each. The weight of the metal in the mold when it strikes the first tripper will generally cause the mold to turn more than ninety degrees as the metal falls 35 from it. The object of the second tripping arm or post p' is merely to even the molds up to an approximately horizontal position as they move past it after discharging the metal. The third tripping-arm p'' may be employed 40 to turn over the molds ninety degrees, after the uppermost mold-recess has been sprinkled or coated with the lime or dope, and in order that the surplus liquid may flow out of the mold-recess and give it a chance to dry, and 45 in order that the next mold-recess which has been coated with the lime or dope some time before (either one, two, or three turns of the wheel earlier) shall be brought into position to be filled with the melted metal.

50 55 I will now explain the operation of the hoods l , by which the molds are rigidly held against turning while they are being filled and while they are traveling to the point where they are overturned and discharged, but which are 60 raised so as to allow the overturning and discharge of the molds when they reach the storage-bin or discharge-point. The hoods l are provided with long guide-pins or guide-rods r , which extend down through guides, 65 that are preferably in the form of pipes or sleeves r' , on the carrier and project beneath the carrier at their lower ends in positions to

be engaged and raised by the stationary inclines s and s' , both of which are shown in Fig. 2, but only one of which is shown in Fig. 70 3. As the two are alike in principle and as they operate in the same manner upon the two pins r of each hood, I will describe the mounting and operation of the incline s . This incline s may advantageously consist of 75 an angle-iron or small I-beam mounted on a fixed support—as, for example, a girder t —and extend for a considerable distance in the path of travel of the lower ends of the outer rods r . Shortly in advance of the position 80 where it is desired to dump the pigs the incline s should commence and rise gradually, as shown in Fig. 3; so that the lower ends of the rods r will engage it and be forced upward, raising the hoods l , as shown in that figure. The incline s may then extend continuously to a point beyond the place where the molds are sprinkled or wet with the dope or protective coating and may then terminate, as seen in Fig. 3, allowing the hoods l to drop as 85 soon as the successive molds have passed clear of the last tripping-arm or tripping-post p'' . In falling the hoods l strike and rest upon the edges of the adjacent molds and bring them into substantially exact horizontal position. 90 Care should be taken that the molds are left in a nearly horizontal position by the action of the last arm or post p'' , so that the hoods l will only have to complete the alignment and serve to hold the molds firmly in position 95 during their filling and their travel from the point where they are filled to the point where they are dumped and discharged. The fixed support or girder t may also serve to carry the tripping arms or posts p p' p'' . The first 100 of these should be placed at the point where the pigs are to be dumped, and the second one should be placed a foot or so farther along. The third post p'' should be placed just beyond the sprinkling or doping apparatus. As 105 the storage-bin is placed directly beneath the point where the molds are discharged, it is convenient to support the girder t either upon the storage-bin or upon the structure that carries the bin. This bin is preferably 110 constructed with a grate-like bottom, which may be formed by a series of inclined rails u , separated by intervals too small to allow the pigs or ingots to fall between and extending from beneath the point where the molds are 115 overturned to discharge downward and sideways toward a convenient point of final delivery—as, for example, above a freight-car w and railroad-track w' . The side of the bin toward the car and the track may consist of a 120 hinged chute v , provided with chains and counterweights v' , forming adjustable means for preventing the pigs from sliding off the bottom and for retaining them in the receptacle. The ends of the bin may be of strong 125 sheet-iron plates x . One, two, or more bins may be provided, a second bin as indicated in dotted lines at u' in Fig. 1. The capacity 130 of two bins may conveniently be one car-load.

The second bin must of course be provided with tripping posts or arms similar to p and p' , and when the second bin is being filled the tripping-posts p p' of the first bin must 5 be removed, so as not to act.

The operation of the apparatus in its preferred form is as follows: Starting with the sprinkler for the lime solution or dope, which sprinkler is indicated in Fig. 1 at z , as a mold 10 passes under the sprinkler its recess that is then turned uppermost is coated with the protective coating. We will assume that the entire apparatus is being rotated sufficiently long to have successively coated all four mold-recesses of each mold. Then as the mold which we are considering passes from under the sprinkler z it is actuated by the tripper-post p'' and turns ninety degrees, so as to discharge the surplus dope or lime and bring a 15 dry mold-recess uppermost. Immediately after this the hoods l of each side of the mold fall and hold it in position as it passes under the chute j , which delivers the molten metal into the molds which have been filled, the 20 metal falling into it, some directly and some off the neighboring hoods l . Then as the hood passes forward the metal within it gradually cools and solidifies while the wheel or carrier is making more than three-quarters 25 of a complete revolution to carry the mold to its point of discharge. Just before the mold reaches the point of discharge the rods r of the hoods l at each side of it are raised by the inclines s s' , so as to enable the mold to 30 be turned. Then the star-wheel m of the mold engages the tripping-post p and overturns the mold, dropping the pig or ingot out of the mold onto the rails u of the storage-bin. Then the mold is turned by the second arm 35 p'' to a horizontal position, with the mold-recess that has just been discharged in the lowermost position, for example. Finally the mold is again brought under the sprinkler and its uppermost recess coated with 40 the protective lime or dope. Under the precise condition stated it would take four complete revolutions of the wheel before the same mold recess or cavity was again used, and this affords abundant opportunity for 45 50 the cooling and drying of the mold. For example, if mold-recess No. 2 in Fig. 6 has just been coated with the protective coating mold recess No. 1 would be filled with the molten metal immediately thereafter, and 55 when the mold is discharged mold-recess No. 3 would be turned uppermost to receive the protective coating. In the second revolution of the carrier-wheel mold No. 2 would be filled with metal, and so on successively, and 60 not until the fifth revolution of the wheel would mold No. 1 be again filled with metal.

From the foregoing it will be seen that the parts marked l and r serve two distinct functions: First, they serve as dividers for the 65 down-pouring stream of molten metal; second, in coöperation with the inclines s and s' they form movable means for holding the

said molds from overturning during a portion of the travel of the said molds, while the inclines s and s' constitute devices for 70 raising or moving such means to release the molds therefrom prior to the discharge of the mold. It will also be seen that the bin or receptacle serves three purposes: First, it constitutes a part of the apparatus in the path 75 along which the metal travels from the time it is poured in the molten state to the time it is finally discharged from the apparatus into the car. It thus constitutes, as it were, a device for prolonging or continuing the duration of the traveling and cooling to which the metal is exposed before it slides from the inclined bottom of the bin. Secondly, by reason of its open-work bottom and the heat of 80 the metal it forms a specific cooling device 85 by which the metal is gradually air-cooled by the rising currents of air. Thirdly, it serves the ordinary and obvious purpose of a storage-bin within which a considerable quantity 90 of the cast metal or other material may be accumulated and stored.

It is clear that some of the novel features of the invention may be used without others; but the best results would be obtained where all the several features described are used 95 together.

Having now particularly described the nature of my said invention and in what manner the same is to be performed, what I claim as the novel and characteristic features, and desire to secure by United States Letters Patent, are the following:

1. In apparatus for casting metal and the like, in which the molds are revolvably mounted on a traveling carrier, the improvement 105 which consists in a hood or divider for the molten metal extending between adjacent molds and normally covering the space between the same, said hood being mounted to travel with the adjacent mold and adapted to 110 hold the same from overturning, and in means which coöperate with the hood or divider for raising it to release the mold to allow it to discharge the cast material.

2. In apparatus for casting metal, in which 115 the molds are revolvably mounted on a traveling carrier, the improvement which consists in a hood or divider for the molten metal extending between adjacent molds and normally covering the space between the same, said 120 hood being supported upon a vertical guide-rod and mounted to travel with the adjacent molds and adapted to hold the same from overturning, means comprising an inclined plane fixed in the path of and adapted to coöperate 125 with the support of the hood or divider for raising it to release the mold to allow it to discharge the casting, and tripping-arms connected with the axis of the mold and corresponding in number with the cavities thereof 130 and adapted to coöperate with a tripping-post after the hood has been raised.

3. In apparatus for casting metal, in which 135 the molds are revolvably mounted on a trav-

- eling carrier, the improvement which consists in a hood or divider for the molten metal extending between adjacent molds and normally covering the space between the same, 5 said hood being supported upon a vertical guide-rod and mounted to travel with the adjacent molds and adapted to hold the same from overturning, means comprising an inclined plane fixed in the path of and adapted 10 to coöperate with the support of the hood or divider for raising it to release the mold to allow it to discharge the casting, and tripping-arms connected with the axis of the mold and corresponding in number with the cavities 15 thereof and adapted to coöperate with a plurality of tripping-posts, whereby any desired mold-cavity may be placed uppermost.
4. The combination of molds adapted to receive molten metal and means for delivering 20 hot castings therefrom, a cooling-bin having side walls, a slatted bottom and an air-space beneath, whereby upwardly-flowing currents of air are induced by the heat of the castings to cool the same.
- 25 5. The combination of molds adapted to receive molten metal and means for delivering hot castings therefrom, comprising a bin

having a slatted bottom, an air-space beneath, side walls, and a discharge-gate, whereby upwardly-flowing currents of air are induced by 30 the heat of the castings to cool the same.

6. The combination with molds adapted to receive molten metal and means for delivering hot castings therefrom, of a cooling-bin comprising an inclined slatted bottom, an air-space beneath, side walls, and a discharge-gate at its lowest point, whereby upwardly-flowing currents of air are induced by the 35 heat of the castings to cool the same.

7. The combination of molds adapted to 40 receive molten metal and means for delivering hot castings therefrom, of a cooling-bin having an inclined slatted bottom, an air-space beneath, side walls, and a discharge-gate at its lowest point, whereby upwardly-flowing currents of air are induced by the 45 heat of the castings to cool the same.

Signed this 13th day of February, 1901, at Canton, Ohio.

RODERICK WASHINGTON DAVIES.
